DESIGN FOR A COMBINED CIGARETTE AND ASH TRAY CASE OR THE LIKE

Adrien Brunschwig, New York, N. Y.

Application October 2, 1944, Serial No. 115,555

Term of patent 14 years

(Cl. D85—2)

To all whom it may concern:

Be it known that I, Adrien Brunschwig, a citizen of the Republic of France, residing in New York city, in the county of New York and State of New York, have invented a new, original, and ornamental Design for a Combined Cigarette and Ash Tray Case or the like, of which the following is a specification, reference being had to the accompanying drawing, forming part thereof.

Fig. 1 is an elevational open view of a combined cigarette and ash tray case or the like showing my design,

Fig. 2 is the top plan view thereof, in closed position, and

Fig. 3 is a perspective side view thereof.

I claim:

The ornamental design for a combined cigarette and ash tray case or the like, substantially as shown.

ADRIEN BRUNSCHWIG.
